CAP FOR MULTIPLE INJECTION DEVICES

William L. Brickson, Indianapolis, Ind., assignor to Bio-Neering, Inc., Carmel, Ind., a corporation of Indiana

Filed June 14, 1968, Ser. No. 12,349

Term of patent 14 years

Int. Cl. D24—03

U.S. Cl. D83—12

FIG. 1

FIG. 2

FIG. 3

FIG. 1 is a side elevation of a cap for multiple injection devices showing my new design;

FIG. 2 is an enlarged elevation thereof;

FIG. 3 is a front elevation thereof.

The broken lines illustrating the injector in FIG. 1 is shown for illustrative purposes only.

I claim:

The ornamental design for a cap for multiple injection devices, as shown and described.
